UNITED STATES PATENT OFFICE.

CHARLES J. SCHMIDT, OF CHICAGO, ILLINOIS, ASSIGNOR TO JUSTRITE MANUFACTURING COMPANY, OF CHICAGO, ILLINOIS, A CORPORATION OF ILLINOIS.

SPARK-PRODUCING MECHANISM.

1,407,225.

Specification of Letters Patent. Patented Feb. 21, 1922.

Application filed June 20, 1921. Serial No. 478,822.

To all whom it may concern:

Be it known that I, CHARLES J. SCHMIDT, a citizen of the United States, and a resident of Chicago, in the county of Cook, 5 State of Illinois, have invented certain new and useful Improvements in Spark-Producing Mechanism, of which the following is a specification.

My invention relates to spark producing 10 mechanism of the type in which a serrated disk or wheel has frictional engagement with a piece of pyrophoric material. The device can be used alone for general lighting purpose as for example, the lighting of 15 gas stoves, lamps, etc., or it can be used as an attachment in connection with wicks for cigar lighters or lamps, or in connection with gas tips as for example the gas tips on miners' acetylene lamps.

20 In the construction and arrangement heretofore used, the serrated disk or friction wheel is adapted only for rotational movement, and a spring is provided for at all times pressing the pyrophoric material 25 against the serrated edge of the wheel. Owing to the spring pressure the sharp teeth or serrations on the wheel frequently are so far embedded in the pyrophoric material that the wheel can be turned only with effort 30 and difficulty and with pain to the operator as the thumb or finger is rubbed across the sharp serrations. Furthermore the constant spring pressure which forces the pyrophoric material against the serrated wheel causes 35 the material to wear away very rapidly.

The important object of my invention is to provide construction and arrangement which will eliminate the spring and all its disadvantages and which will permit the 40 friction disk to move bodily as well as rotate axially. Instead of trunnioning the wheel snugly in cylindrical trunnion holes, I provide trunnion slots which extend at such angle that when pressure is applied on the 45 wheel to force it toward the pyrophoric material it will tend to roll with its trunnion shaft along the slots in a direction away from the pyrophoric material, the angle however being such that downward pressure 50 on the wheel will eventually predominate and the wheel will be pressed with sufficient frictional engagement against the pyrophoric material to produce the necessary 55 sparking for ignition purposes. I provide an adjustable abutment for holding the

pyrophoric material within range of the wheel when pressure is exerted thereon, but under lighter pressure the wheel can be readily spun around, and when rotated with the finger it will strike the pyrophoric material 60 with considerable momentum at the time of its frictional engagement therewith to produce the sparks.

On the accompanying drawings which 65 clearly describe my invention,

Fig. 1 is a side elevational view of a hand lighter which can be used for general lighting purposes,

Fig. 2 is a vertical diametral sectional view taken on a plane parallel with the friction disk,

Fig. 3 is a sectional view on plane 3—3, Fig. 1,

Fig. 4 is a front elevational view of a miner's cap lamp showing the sparking attachment thereon, and

Fig. 5 is a sectional view on plane 5—5, Fig. 4 of the lamp reflector and the sparking attachment thereon.

The sparking device comprises the tube or 80 barrel 10 which at its upper end is enlarged and bifurcated to provide the opposed wall sections 11 and 12 between which is positioned the serrated disk or friction wheel 13, the wheel being preferably of steel with 85 points or teeth formed in its cylindrical periphery. The wheel has the central trunnion pin 14 which extends into the enlarged trunnion openings or slots 15 and 16 in the walls 11 and 12. When the trunnion openings are 90 in the form of slots, these slots are inclined at an angle with the axis of the tube 10, the inclination being such that when the wheel is turned by engagement with its periphery, the trunnion pin will tend to roll up on the 95 lower walls of the slots so that the wheel will partake of a bodily movement as well as a rotary movement.

The tube 10 has the external thread 17 at its lower end for receiving a cap 18 from 100 which extends the abutment rod 19 through the tube 10. The rod or stem 19 serves as an abutment for the cylinder or block 20 of pyrophoric or other spark producing material, the material being held by the 105 stem 19 within range of the friction wheel when it is rotated, so that the wheel may exert frictional pressure thereon to produce the sparks. By turning the cap 18 on the tube the stem 19 can be adjusted longi- 110

tudinally and the adjustment is preferably kept such that the pyrophoric material will be held at a sufficient height to engage the periphery of the friction wheel to normally hold its trunnion pin at some point intermediate the ends of the slots. The wheel is rotated in the direction which will tend to roll the trunnion pin upwardly along the lower edges of the slots, that is, in a direction bodily away from the pyrophoric material. The thumb or finger is applied to the roughened periphery of the friction wheel and the wheel is given one or more rapid rotations under pressure. The inclined slots will tend to cause the wheel to roll bodily away from the pyrophoric material but the pressure on the wheel toward the pyrophoric material will eventually predominate, and the wheel while being rapidly rotated will be suddenly brought down against the pyrophoric material and sufficient sparking will result but without sticking of the wheel points on the pyrophoric material. At the end of each engagement of the thumb or finger with the wheel it will spin freely after release, and it is then entirely loose from the pyrophoric material ready for another pressure engagement therewith. This operation is entirely impossible where a spring is used to at all times firmly press the pyrophoric material against the wheel, for then the sharp points of the wheel become embedded in the material and the wheel can be rotated only with heavy pull and pressure and most times with considerable pain to the operator. With my improved arrangement the wheel is free and loose at all times and engages under pressure with the pyrophoric material only after it has acquired considerable momentum. To facilitate and ease the operation of the wheel the upper corners of the walls 11 and 12 are well rounded and the walls at their tops are preferably parallel with the slots. There is therefore no chance for injury to the fingers.

In Figs. 4 and 5 I have shown the sparking device somewhat modified to adapt it for application to the reflector of a miner's cap lamp. The lamp shown has the usual body 21 on which is mounted the reflector 22 at the center of which is the gas outlet or tip 23 for gas generated within the lamp body. The sparking attachment is substantially of the same construction as that shown in Figs. 1, 2 and 3. The tube 10 is threaded its entire distance and is extended through the hole 24 in the reflector so that the walls 11 and 12 may engage at their base against the inner face of the reflector. A nut 25 engages the threaded tube and abuts against the outer face of the reflector, the attachment being thus securely held in place. The walls 11 and 12 are parallel with the radial plane of the tip 23 and the slots 15 and 16

extend in such direction that when the thumb or finger applied to the top of the wheel is drawn outwardly the wheel will tend to roll bodily toward the higher ends of the slots and away from the pyrophoric material. However, under sufficient pressure the rotating wheel will eventually frictionally encounter the sparking material and the generated sparks will be shot toward the gas outlet 23 to ignite the issuing gas.

The lighting attachment can also be so positioned with reference to the reflector edge that the lamp can be ignited by palming, that is, by applying the palm of the hand against the reflector edge and over the wheel, and drawing the hand suddenly away and at the same time rotating the wheel, after gas has accumulated in the pocket formed by the reflector and the hand. My improved lighter attachment is particularly adaptable for this method of ignition owing to the freedom of movement of the friction wheel.

I thus produce a simple, practical and efficient sparking device or attachment. The spring and all its disadvantages are eliminated. The friction wheel never sticks but can always be freely and efficiently operated to produce good sparking. By eliminating the spring and its incessant pressure against the spark wheel the wastage of pyrophoric material is eliminated, there being just sufficient engagement between the spark wheel and the pyrophoric material to produce just enough sparks for ignition purposes. I do not desire to be limited to the precise construction and arrangement shown and described as changes and modifications can be made which will come within the scope of the invention.

I claim as follows:

1. In a lighting device of the class described, the combination of a friction disk rotatable on its axis, sparking material below said disk, means for holding said sparking material within range of said disk when rotated, and means tending to cause said disk when rotated to be raised from said sparking material to thereby decrease the friction of engagement between said disk and material.

2. In a lighting device of the class described, the combination of a rotatable friction disk, sparking material, means for holding said sparking material in fixed position below said disk, said disk normally engaging said material, and means tending to raise said disk from said material when said disk is rotated against said material to thereby decrease the friction and prevent sticking of the disk.

3. In a lighting device of the class described, the combination of a supporting frame having opposed walls, a friction disk between said walls, a trunnion pin for said

- disk, diagonally inclined slots in said walls for receiving said pin, and means for supporting sparking material on said frame in range of said disk, said inclined slots tending 5 to cause said disk to move bodily away from said sparking material when rotational pressure is applied to the disk.
4. In a lighting device of the class described, the combination of a supporting frame having opposed walls, a friction disk between said walls, spark producing material held in said frame below said disk, a trunnion pin for said disk, bearing surfaces on said walls for said pin inclined in a direction tending to cause said disk to be raised away from said material when said disk is rotated, whereby said disk may be released from said material before it is brought into spark producing engagement therewith.
- 10 5. In a lighting device of the class described, the combination of a supporting frame, said frame having a bore, a non-yielding abutment in said bore, spark producing material seated on said abutment, opposed walls on said frame above said material, a friction disk between said walls and above said material, and a trunnion pin for said disk, said walls having upwardly inclined slots for receiving said pin, said disk 25 projecting beyond said walls to be engaged and rotated by the hand, said disk engaging with said material when its trunnion pin is away from the upper end of the slots, said slots causing the disk to be raised from the material when it is moved toward the upper end of the slots.
- 30 6. In a lighting device of the class described, the combination of a supporting frame, opposed walls on said frame, spark producing material within said frame, means for rigidly supporting said material at the base of said walls, a combined thumb wheel
- and friction disk between said walls, a trunnion pin for said disk, said walls having diagonally inclined slots for receiving the 45 ends of said pin, said pin tending to move down said slot to permit the wheel to engage with the spark producing material, and said slots permitting said wheel to be moved bodily away from said material when it is 50 rotated.
7. In a lighting device of the class described, the combination of a frame, a sparking element seated in said frame, a combined thumb wheel and friction disk in said frame 55 above said sparking element, and diagonally inclined pivot slots for said wheel in said frame for permitting said wheel to be moved bodily toward or away from said sparking element when the wheel is rotated.
8. In a lighting device of the class described, the combination of a supporting frame, opposed walls on said frame, a rigid abutment on said frame below said walls, spark producing material seated on said 65 abutment, a friction wheel between said walls, a trunnion pin for said wheel, diagonally extending bearing surfaces on said walls for said pin, said pin moving down said surfaces when said wheel is pressed toward 70 said spark producing material to permit the wheel to frictionally engage with the sparking material and to cause sparks when it is rotated, said pin tending when rotation of the wheel is resisted by said material to roll 75 up along said surfaces to decrease the frictional engagement of the wheel with the material to thereby prevent sticking of the wheel.
- In witness whereof, I hereunto subscribe 80 my name this 13th day of June, A. D., 1921.

CHARLES J. SCHMIDT.
